Attorney

UNITED STATES PATENT OFFICE.

JOHN W. BRAGGER, OF WATERTOWN, NEW YORK, ASSIGNOR TO THE
HITCHCOCK LAMP COMPANY, OF SAME PLACE.

FLUSHING-VALVE.

SPECIFICATION forming part of Letters Patent No. 597,946, dated January 25, 1898.

Application filed June 11, 1897. Serial No. 640,358. (No model.)

To all whom it may concern.

Be it known that I, JOHN W. BRAGGER, a citizen of the United States, residing at Watertown, in the county of Jefferson and State of New York, have invented certain new and useful Improvements in Flushing-Valves; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in water-closet-flushing valves, and in carrying out the present invention it is my purpose to generally improve upon constructions of flushing-valves common in the art and also upon the valve upon which I have a pending application.

More specifically this invention consists in the provision of a piston provided with a suitable stem which is adapted to work within a suitable shell or casing and a valve-regulated duct leading from one side of the piston to the other at the highest point of the shell, whereby the water contained within the casing or shell outside of the piston may be forced through the said duct as the flushing-valve is opened, and in a reverse movement of the piston, as in the closing of the supply-valve, the latter will be retarded slightly, owing to the partial vacuum, which is broken only by the small quantity of water that is allowed to enter the vacuum-space.

To these ends and to such others as the invention may pertain the same consists, further, in the novel construction, combination, and adaptation of the parts, as will be herein-after more fully described, and then specifically defined in the appended claims.

The invention is clearly illustrated in the accompanying drawings, which, with the letters of reference marked thereon, form a part of this specification, and in which drawings—

Figure 1 is a plan view of my improved flushing-valve, showing the outside casing. Fig. 2 is a central vertical longitudinal sectional view through the device.

Reference now being had to the details of

the drawings by letter, A designates the shell or casing of the flushing-valve and is provided at one end with a screw-threaded cap A' and with inlet-passage A⁴ and outlet-passage A⁵ and a valve-seat A³, which is integral with the shell. Mounted within the shell is a piston-stem C, one end of which is provided with a piston or plunger A⁶, made up of two plates which have suitable packing between 55 same and are held against a shoulder on the stem by a threaded nut D'. This piston is designed to work in an enlarged end portion of the shell or casing, as illustrated in the drawings.

65 Communicating with the space in the casing on opposite sides of the piston is a duct F³, and at the entrance to the said duct and vertically disposed is a valve F, which is designed to be seated against the seat F', which 70 may be formed by a screw-threaded plug and fitted in the aperture provided therefor. In order to regulate the said valve and prevent it from fully closing, I provide a set-screw G, the lower end of which may be presented in 75 the path of the valve, as shown. This screw is carried in the screw-threaded plug F², and a suitable cap G' is fitted in the outer end of the aperture provided to receive the valve to prevent leakage and by removing which access may be had to the said valve and adjusting set-screw.

80 At the opposite end of the shell or casing is provided the stem-receiving casting in which the stem is guided, and which casting 85 B may be held to the shell A by a suitable union B'. Between the ends of the said shell and casting is located the diaphragm D⁴, of ordinary construction common in the art, which is held to the stem by suitable washers D³ and nut D², the said washers being forced against a shoulder on the stem. In order to allow sufficient play to the diaphragm, the ends of the shell and casting are hollowed out, as shown. Within the casting and carried on the stem C is a coiled spring E', one 90 end of which bears against the inner end wall of the casing, while its other end bears against set-nuts E, mounted on the screw-threaded portion of the stem, by which the 95 tension of the spring may be regulated when it is desired to balance the valve C², which 100

allows the water from the inlet-passage to pass through into the outlet-pipe A⁵.

The operating-lever K, which is fulcrumed on a pin carried in an aperture K⁴ in the casting, is held on a stud K' on the side of the casting and has a vertical play limited by the elongated slot or aperture in the lever. By means of the set-screw L the throw of the lever may be regulated. A suitable nut M holds the lever on the stud, and a jam-nut may be mounted on the set-screw, as shown. At one end of the lever is bolted, at the end of the casting, an arm N, the angle at which it is desired to have the same held being capable of being regulated. This arm is designed to bear against the end of the piston-stem as the lever is raised, as will be understood.

In operation when the lever is raised, the stem and piston are forced back and the water, entering the shell through the inlet-passage, exerts pressure (due to the crank) upon the flat face of the valve C² and static pressure upon the face of the piston A⁶ next the valve. The latter pressure being great, it will hold the valve open until it is nearly or quite balanced by pressure upon the opposite face of the same piston, due to water passing slowly through the duct F³ and by the valve F.

The valve can therefore move to its seat only as fast as the enlarging space on the side of the piston opposite the valve can be filled. An advantage is derived in having the duct F³ at the extreme upper portion of the shell, so that the air which may be confined in the enlarged end will be forced out when the plunger is operated. If the valve F be placed in the central portion of the piston, the air, of which there is more or less forced through the pipes with the water, would be trapped in the top, and as the elasticity of the air is so great

the valve does not operate successfully, but by placing the duct as hereinbefore described the difficulty is overcome.

Having thus described my invention, what I claim to be new, and desire to secure by Letters Patent, is—

1. In combination with the shell, having the piston-stem and piston mounted thereon, the enlarged portion in which the latter works, the valve-regulated duct and valve and seat therefor as described, the casting B in which one end of the stem is held and guided, a spring about the stem within a hollow portion of the said casting, set-nuts for regulating the tension thereof, the diaphragm, the adjacent ends of the said shell and casting being concaved to receive said diaphragm, and the union connecting the said shell and casting, and means for operating the piston-stem, substantially as shown and described.

2. In combination with the flushing-valve shell, of the valve and stem working therein, the stud integral with the shell, the casting connected to the shell, the operating-lever pivoted to a bolt at one end of the casting and provided with a transversely-disposed slot adapted to work on the said stud, a nut on said stud adapted to hold the lever thereto, a set-screw mounted in the handle at one end of the said slot and an arm pivoted at one end of the lever and which is designed to bear against the end of the piston-stem as the lever is operated, substantially as shown and described.

In testimony whereof I affix my signature in presence of two witnesses.

JOHN W. BRAGGER.
